UNITED STATES PATENT OFFICE

2,165,633

BOAT

John D. Hunt, Alexandria Bay, N. Y.

Application October 25, 1938, Serial No. 236,928

3 Claims. (Cl. 114—43)

The present invention relates to new and useful improvements in boats and has for its primary object to provide, in a manner as hereinafter set forth, a vehicle of this character which is adapted to travel on snow and ice as well as water.

Another very important object of the invention is to provide, in a boat comprising retractable runners for travelling over snow and ice, a mechanism of a novel construction and arrangement for actuating said runners to operative and inoperative position.

Still another very important object of the invention is to provide a boat of the aforementioned character embodying novel means for yieldingly mounting the hull on the runners thereby permitting the vehicle to travel over rough ice without being damaged thereby or causing discomfort to the occupants thereof.

Other objects of the invention are to provide a boat of the character described which will be comparatively simple in construction, strong, durable, highly efficient and reliable in use, compact and which may be produced at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a boat embodying the present invention, the major portion thereof being broken away in vertical longitudinal section.

Figure 2 is a cross sectional view, taken substantially on the line 2—2 of Fig. 1.

Figure 3 is a view in vertical section through one of the runners and the resilient mount therefor, taken substantially on the line 3—3 of Fig. 4.

Figure 4 is a view in side elevation of the portion of the invention shown in Fig. 3.

Figure 5 is a detail view in perspective, showing the pin and slot connection between the hand lever and one of the cam operating bars.

Figure 6 is a cross sectional view, taken substantially on the line 6—6 of Fig. 1.

Figure 7 is an elevational view of a modified form of cam operating means.

Figure 8 is a top plan view of one of the runner supports.

Referring now to the drawings in detail, it will be seen that the embodiment of the invention which has been illustrated comprises a hull 1 of the type shown to advantage in Figs. 1 and 2 of the drawings. Rigidly secured, as at 2, to the

bottom 3 adjacent each side of the hull 1 is a series of vertical guides 4 which communicate with openings in said bottom 3, said guides having suitable lubricating fittings 5 therein. Posts 6 are slidably mounted in the guides 4, said posts 5 projecting downwardly through the openings provided therefor in the bottom 3 of the hull 1 and having fixed on their lower end portions runners 7.

The runners 7 are of suitable resilient material 10 and, as best seen in Fig. 1 of the drawings, said runners conform substantially to the longitudinal curvature of the bottom 3 of the hull 1. The upwardly curved forward end portions of the runners 7 extend between pairs of guides 8, which 15 are provided therefor beneath the bow of the hull 1. Extending between each pair of guides 8 is a pair of rods or the like 9 (see Fig. 1) between which the end portions of the runners 7 are operable. Stops 10 are provided on the forward ends of the runners 7 for preventing said runners from being withdrawn rearwardly from between the elements 9.

Rising from the vertical posts 6 are stems 11 having discs 12 slidably mounted on their upper 25 portions. Depending from the discs 12 are sleeve bearings 13. Inner and outer coil springs 14 and 15, respectively, are provided beneath the discs 12. The inner coil springs 14, it will be noted, have their lower ends engaged on the upper ends 30 of the posts 6 and the outer coil springs 15 rest on the upper ends of the guides 4. Retaining nuts 16 for the discs 12 are threaded on the upper end portions of the stems 11. The posts 6 are provided with suitable packing rings 17 for 35 preventing leakage therearound. Pairs of rollers 18, the purpose of which will be presently set forth, are mounted on top of the discs 12.

Mounted on the bottom 3 of the hull 1 on opposite sides of the guides 4 are pairs of substantially U-shaped inclined standards 19 comprising upstanding arms 20 on their upper ends. Extending between the pairs of arms 20 are pins 21 and journaled thereon are cams 22 in the form of rings which are operatively engaged with the 45 rollers 18 on the discs 12. The upper portions of the cams 22 bend inwardly and merge, as at 23, and rising therefrom is an operating arm 24.

The reference numeral 25 designates a bar or rod which connects the cams 22 of each series 50 for operation in unison. A transverse shaft 26 (see Fig. 2) is journaled for rocking movement in the rear portion of the hull 1. Fixed on the end portions of the shaft 26 are arms 27. The rods 25 are operatively connected to the free 55

end portions of the arms 27 through the medium of links 28. Thus, the bars 25 on both sides of the hull 1 are connected for operation in unison. The reference numeral 29 designates a hand lever which is operatively connected, at an intermediate point, to one of the rods 25 through the medium of a pin and slot connection 30. This pin and slot connection is shown to advantage in Fig. 5 of the drawings.

10 It is thought that the operation of the invention will be readily apparent from a consideration of the foregoing. When the boat is travelling on water the posts 6 are held in raised position by the coil springs 14 and 15 thereby holding the runners 7 in raised or inoperative position closely adjacent the bottom 3 of the hull, as shown in full lines in Fig. 1 of the drawings. However, when the vehicle is to travel over snow or ice the runners 7 are lowered to operative position, as suggested in broken lines in Fig. 1 of the drawings. This is accomplished by swinging the hand lever 29 forwardly as seen in Fig. 1 of the drawings, thus rocking the cams 22 in a manner to force the discs 12 downwardly on the stems 11.

15 25 When this occurs the inner springs 14 push the posts 6 downwardly in the guides 4 through the bottom 3 of the hull thereby lowering the runners 7 to operative position. With the runners 7 in operative position, the weight of the hull 1 is carried by the inner coil springs 14. It will thus be seen that a resilient mounting is had which will permit the vehicle to travel over rough ice or snow without being damaged from shock or vibration and with minimum discomfort to the

20 30 35 occupants. When the hand lever 29 is swung in the opposite direction, or rearwardly, the cams 22 are actuated in a direction to permit the coil springs 14 and 15, particularly the latter, to retract or raise the runners 7 to inoperative position again. The rudder is propelled by an air screw 31. An air rudder 32 is provided rearwardly of the screw 31.

In the slight modification shown in Fig. 7 of the drawings, a hand wheel 33 is substituted for the lever 29. The hand wheel 33 is fixed on a shaft 34 which is journaled horizontally on a suitable support 35. Also fixed on the shaft 34 is a sprocket gear 36. A sprocket chain 37 is trained over the sprocket gear 36 and is connected at its ends, as at 38, to the adjacent rod 25. Thus, by rotating the hand wheel 33 the adjacent rod 25 is shifted forwardly or rearwardly.

It is believed that the many advantages of a boat constructed in accordance with the present invention will be readily understood and although preferred embodiments are as illustrated and described, it is to be understood that further modi-

fications and changes in the details of construction may be resorted to which will fall within the scope of the invention as claimed.

What is claimed is:

1. A boat of the class described comprising a hull including a bottom, vertical guides rising from the bottom, vertically movable posts slidably mounted in the guides and operable through the bottom of the hull, runners mounted on the lower ends of the posts beneath said bottom of the hull, pairs of standards mounted adjacent the guides, pairs of cams journalled between said pairs of standards, vertical stems rising from the posts, discs slidably mounted on the stems and engaged with the cams for downward actuation thereby, coil springs yieldingly connecting the posts to the discs for downward actuation thereby, coil springs mounted between the guides and the discs for raising the posts, and manually operable means for actuating the cams in unison. 20

2. A boat of the class described comprising a hull including a bottom, vertical guides rising from the bottom, vertically movable posts slidably mounted in the guides and operable through the bottom of the hull, runners mounted on the lower ends of the posts beneath said bottom of the hull, pairs of standards mounted adjacent the guides, pairs of cams journalled between said pairs of standards, vertical stems rising from the posts, discs slidably mounted on the stems and engaged with the cams for downward actuation thereby, coil springs yieldingly connecting the posts to the discs for downward actuation thereby, coil springs mounted between the guides and the discs for raising the posts, and manually operable means for actuating the cams in unison, said manually operable means comprising arms 25 30 35 fixed to the cams, rods operatively connected to said arms, a rocker shaft operatively connected to the rods for actuating said rods in unison, and a hand operated member operatively connected to one of the rods. 40

3. A boat of the class described comprising a hull including a bottom, vertically movable posts extending slidably through said bottom, runners on the lower ends of said posts, a plurality of cams, resilient means operatively connecting the posts to said cams for downward actuation thereby, rods operatively connecting certain of the cams together for actuation in unison, means 45 operatively connecting said rods together for operation in unison, a hand wheel, a sprocket gear connected to said wheel for actuation thereby, and a sprocket chain trained over said sprocket gear and connected, at its ends, to one of the 50 rods for actuating same. 55
